[57] CLAIM

The ornamental design for a shovel, as shown and described.

DESCRIPTION

FIG. 1 is a diagrammatic perspective view of the shovel;
FIG. 2 is a top plan view of the shovel;
FIG. 3 is a bottom plan view thereof;
FIG. 4 is a front elevational view thereof;
FIG. 5 is a rear elevational view thereof; and,
FIG. 6 is a right side elevational view of the shovel, the left
side view being a mirror image of the right side view.
